[57] CLAIM

The ornamental design for a hobo doll, as shown and described.

DESCRIPTION

FIG. 1 is a view in front elevation of a hobo doll showing my new design;

FIG. 2 is a view in rear elevation of the claimed design;
FIG. 3 is a view in side elevation of the claimed design, looking from right to left in FIG. 1; and,

FIG. 4 is another view in side elevation of the claimed design, in this instance, however, looking from left to right in FIG. 1.

FIG. 1

FIG. 4
